UNITED STATES PATENT OFFICE

LESTER L. JONES, OF ORADELL, NEW JERSEY

RADIOFREQUENCY CIRCUITS

Application filed October 5, 1929. Serial No. 397,632.

This invention relates to radio frequency circuits and more particularly to coupling means for successive vacuum tubes employed in radio receiving circuits.

5 In my copending application, Ser. No. 205,934, filed July 15, 1927, since issued on July 15, 1930, as Patent No. 1,770,525, I have disclosed a radio receiving circuit comprising a selector or tuning means having variable 10 circuit constants followed by a vacuum tube amplifier having fixed circuit constants, and a coupling means therein arranged to prevent reaction by the amplifier on the selector. The primary object of my present invention is to 15 improve such reactionless coupling means used between any successive vacuum tubes, and more especially to improve the coupling means used in a radio receiving circuit such as is disclosed in the said copending application.

To the accomplishment of the foregoing and such other objects as will hereinafter appear, my invention consists in the circuit elements and their relation one to the other as 25 hereinafter are more particularly described in the specification and sought to be defined in the claims. The specification is accompanied by drawings in which:

Fig. 1 illustrates my invention applied to 30 impedance coupled tubes;

Fig. 2 illustrates the invention applied to 35 transformer coupled tubes;

Fig. 3 is a modification of the arrangement shown in Fig. 2;

Fig. 4 is a series of graphs explanatory of 40 my invention;

Fig. 5 is a schematic wiring diagram for a 45 radio receiving circuit embodying my invention; and

Fig. 6 is a schematic wiring diagram for a 50 different receiver circuit further embodying my invention.

Referring to Fig. 1, which is a fragmentary portion of a complete wiring diagram, it will 55 be observed that the anode 4 of a vacuum tube 2 is connected to a source of anode current through an inductance 6. This inductance is of such magnitude and construction that it causes the output circuit of the tube 50 to be naturally resonant to a frequency higher

than the highest frequency of the working frequency range in which the circuit is to be employed. The output circuit is therefore always inductive and therefore always regenerative.

To counteract for this regenerative effect suitable neutralizing means may be employed, which preferably may take the form of a resistance 8, which is desirably made 55 capacitance and inductance free, and of appropriate magnitude to cause a feed forward current through the tube 2 which opposes and neutralizes the regenerative feed back current, all as has been set forth more in detail in my U. S. Patent No. 1,713,130 60 issued May 14, 1929. 65

As in the case of the circuit set forth in my copending application, Ser. No. 205,934, already referred to, the succeeding vacuum tube 10 is coupled to the output circuit of the 70 vacuum tube 2 through a capacitance 12 and an inductance 14, the coupling inductance 14 being connected across the cathode and control electrode of the tube 10, and serving incidentally to determine the 75 bias potential thereof, while the capacitance 12 is connected between the output circuit of the tube 2 and the control electrode of the tube 10. The capacitance 12 and inductance 14 are preferably so dimensioned as to be series resonant to a frequency lower than the 80 lowest frequency of the working frequency range, whereby there is a tendency to increase the amplification of the lower frequency signals.

When only a single tube as, for example, the tube 2 so far described, is used as a 85 reactionless link the tube is relatively inefficient as an amplifier stage. This is so because the preferably capacitance and inductance free resistance 8 is given a magnitude approximately equal to the impedance of the tube divided by the amplification constant thereof, as is explained in my Patents Nos. 1,713,130 and 1,713,132. The resistance 90 therefore is only of the order of a thousand to two thousand ohms in the case of ordinary present day amplifier tubes, for example, tubes of the 227 type having an inter-electrode capacitance of the order of three M. M. 95 100

F., an amplification constant of the order of 12, and a tube impedance of the order of 10,000 ohms. Also, the inductance 6 is small, being given a value determined by the relationship that it, together with the capacitance hanging onto the high potential end of the output circuit, is to be naturally resonant to a frequency at or slightly higher than the highest frequency of the working frequency range. The foregoing relative values of inductance and resistance may, of course, be slightly varied to more accurately balance the feed back reaction due to the inductance and the feed forward reaction due to the resistance. Now, while such a reactionless stage is workable it is not as efficient an amplifier stage as might be desired because the total impedance in the output circuit is only a fraction of the tube impedance instead of being equal to or larger than the tube impedance, as it should be for maximum amplification.

Furthermore, when a reactive load is coupled to the output circuit its upsets the balance of reactions, and to overcome this by the method taught in my Patent No. 1,620,661, issued March 15, 1927, by tapping the succeeding circuit into the resistance at an intermediate point thereof such that feed forward and feed back reactions are balanced, still further reduces the amplification owing to the resulting reduced coupling obtained between the output and the succeeding circuits. In order to increase the gain obtainable I first couple the succeeding circuit to the plate end of the resistance, thereby obtaining the maximum coupling between the circuits.

But of greater importance, in order to raise the gain obtainable in the transition or reactionless link tube 2 I find it feasible to increase by approximately two-fold the resistance and inductance values suggested above, the resistance then being of the order of 2800 ohms, and the inductance being of the order of 230 microh. This approximately doubles the impedance of the output circuit and approximately doubles the gain in the tube.

To explain this more in detail, the desired resonance frequency may be obtained by either a relatively large inductance in parallel with a relatively small capacitance or a relatively small inductance in parallel with a relatively large capacitance. I intentionally select a large inductance, and to make this possible intentionally reduce the capacitance in parallel therewith. This capacitance may be reduced, first, by the use of tubes having a low inter-electrode tube capacitance, and second, by reducing the external capacitance by refinements in the construction of the apparatus, such as the use of short leads, the reduction in area and linear dimension of the resistance 8 and the capacitance 16, and the

location of these parts as far as possible from other parts which are at ground potential. The increased inductance results in a larger output circuit impedance at frequencies in the working frequency range and this results in better amplification. The larger output inductance incidentally causes augmented feed back which necessitates a larger resistance in order to obtain augmented feed forward energy, for opposing the feed back energy. The increased magnitude of the feed forward resistance 8 also increases the impedance of the output circuit of the tube, and therefore also leads to better amplification. The capacitance necessarily hanging onto the anode end of the output circuit causes feed forward and damping or degeneration, to avoid which the resistance 8 may be increased slightly less than proportionally to the increase in inductance 6.

When the above changes for higher efficiency amplification are made there still appear in the input circuit of the tube slight variations from the zero reaction condition. The major of these variations is a tendency toward regenerative feed back on low frequencies, and damping or feed forward on high frequencies. This can be generally corrected by causing a decreasing capacitance from plate to ground with increasing frequency.

This is accomplished, as has already been explained in my copending application, Ser. No. 205,934, since issued as Patent No. 1,770,525, already referred to, by suitably arranging the output circuit of the following tube, although the specific quantitative dimensions there given differ somewhat, being applicable to tubes of the 201A type, having an amplification constant of approximately 8, an inter-electrode tube capacitance of approximately 8 M. M. F., and a tube impedance of approximately 8000 ohms.

Tube 10 in Fig. 1 has connected in series with its anode an inductance 11 which is a relatively large inductance, so dimensioned as to be naturally resonant, together with the capacitance hanging thereon, to a frequency lower than the working frequency range.

If it is the primary of a transformer, as is usually the case, the transformer should preferably be bifilar wound. The working frequencies are then higher than the resonant frequency, and for these frequencies the output circuit is effectively capacitive, and therefore is of decreasing impedance with increasing frequency, which causes a decreasing apparent input capacitance with increasing frequency. The capacitance therefore varies in opposite sense to the frequency and in the same sense as the wave length. This change in capacitance is in the proper sense for automatically tuning the input circuit of tube 10, but the capacitance is preferably made in excess with a view to obtaining capacitance hanging onto the output circuit of tube 2. The input

5 capacitance of tube 10 is transferred directly to the output circuit of tube 2 by the coupling means therebetween, and the said capacitance alters the constants of the output circuit of tube 2 in the proper direction to correct for the major residual or disturbing reactions caused by the increase in the inductance 6 and resistance 8 of the output circuit of tube 2 above the values specified in my aforesaid 10 patents to prevent reaction through the tube. There still remain minor variations, with which I shall next deal.

15 One of such minor variations is a tendency toward regenerative feed back in the middle of the working frequency band. To correct this, in accordance with my present invention a capacitance 16 is arranged in shunt or parallel with the feed forward resistance 8, and this capacitance I have empirically found serves the function of causing a decreased regenerative action in the middle of the band. Its advantages are particularly applicable to a vacuum tube 20 amplifier, preceded by a very sharply tuned circuit, the condenser 16 serving to make the effect of the reaction of the amplifier on the sharply tuned circuit more nearly like that of a fixed loss free condenser of small capacitance.

25 30 As stated, without the fixed condenser 16 the input characteristic of the tube usually shows a regenerative tendency in the middle of the working frequency band. The magnitude of this tendency is generally of such an order as would decrease the damping of the sharply tuned input circuit to one half of its normal damping when all the constants are set so as to provide for the absence of reaction at the upper and lower extremes of the working frequency band. The addition 35 of the condenser 16 permits the elimination 40 of this slight regenerative tendency without any appreciable sacrifice of gain and without the introduction of any other operating disadvantage.

45 In Fig. 2 I have illustrated a modified form of the invention which employs transformer coupling between stages, and which possesses certain advantages for that reason.

50 One of these is that the elimination of the condenser 12 eliminates a part having a high capacitance to ground and therefore reduces the capacity shunt across the output circuit of the tube and so improves the efficiency thereof, a bifilar wound transformer being 55 no worse than a single inductance as regards its capacitance to ground. Another advantage of the transformer coupling is that the circuit may be built more compactly. A 60 third advantage of the transformer coupling resides in the fact that it provides a low resistance shunt path around the output circuit through which the steady component 65 of the plate current may flow even though the inductance of the transformer is so great

relative to the output inductance 6 that the latter essentially determines the impedance of the output circuit with respect to radio frequency energy. To explain this more in detail, in Patent No. 1,713,130, May 14, 1929, I have stated that the magnitude of the series resistance 8 is preferably of the order of the output impedance of the tube divided by the amplification constant. When the condenser 16 is added it becomes possible to increase the value of the resistance 8 to a value approximately twice the value above defined, without introducing any appreciable reaction in the tube. This increases the impedance of the output circuit and therefore increases the amplification gain.

70 75 It is generally advantageous in this class of amplifier to use tubes having relatively low output impedance. These tubes draw considerable plate current. It therefore follows that with the augmented value of resistance 8 there is a considerable power loss in the series resistor as well as a fair voltage drop so that a slight loss of amplification results due to the lower average potential 80 on the plate.

85 90 The aforesaid third advantage of the transformer coupled arrangement is that it makes possible the provision of a low resistance shunt path around the series resistance 8 and impedance 6, through which the constant component of plate current can flow. This substantially eliminates the above described energy loss and voltage drop in the plate circuit, and thereby tends to slightly increase the amplification obtained as well as to provide greater freedom in the choice of the resistor 8. By this I mean that this resistor may thereby be made physically smaller, since there is no appreciable power dissipation to be taken care of, and this, in turn, further reduces the inherent capacity shunt across the output of the tube, thereby increasing its efficiency.

95 100 105 A fourth advantage of the transformer coupled arrangement is that the inductance thereof may be optionally selected over a very wide range, and it is therefore quite simple to choose for its inductance a value which will be suitably related to the apparent input capacitance of the following tube, and to the changing capacitance there obtained, to result in a helpful amount of automatic tuning of the input circuit of the following tube.

110 115 120 125 130 A fifth advantage is peculiar to the use of a bifilar transformer or its equivalent, that is, a unity coupling or very closely coupled transformer, and resides in the fact that such a transformer transfers the changes in input capacitance of the following tube directly across to the output circuit of the preceding or link tube, and therefore is ideally suited for correcting the residual reaction which it has already been explained tends to arise

when the output resistance and inductance of the link stage is raised with a view to increasing the amplification gain therein.

Referring to Fig. 2, the first vacuum tube 2 has its anode 4 connected to the primary of a bifilar wound transformer 20, the secondary of which is connected to the cathode and control electrode of a second vacuum tube 10. Across the primary of the transformer 20 there is connected a shunt circuit consisting of a resistance 8 connected in series with an inductance 6, while a capacitance 16 is arranged in parallel with the resistance 8. Inductance 11 corresponds to inductance 11 in Fig. 1.

In one aspect we may say that the output circuit of the tube 2, in both Fig. 1 and Fig. 2, consists of an inductance 6 of suitable dimension and construction to cause the reaction of the tube in the working frequency range always to be regenerative, together with a neutralizing or feed forward resistance 8, and that the output from tube 2 is fed to a succeeding tube 10 through the coupling circuit 12, 14, in Fig. 1, or the transformer 20, in Fig. 2, while the operating and reactional characteristics of the circuit are improved by the addition of a capacitance 16 arranged in shunt with the resistance 8. In another aspect it may be stated, both with respect to the arrangements shown in Fig. 1 and Fig. 2, that the coupling means between successive vacuum tube stages, which may be impedance coupling, as in Fig. 1, or transformer coupling, as in Fig. 2, is additionally provided with a complex shunt circuit, said shunt circuit consisting of an inductance arranged in series with a capacitance and a parallel connected resistance. I believe the first viewpoint is the more correct, technically, and better explanatory of the operation of the circuit.

The arrangement shown in Fig. 3 corresponds very closely with that shown in Fig. 2 except for the fact that the lower terminal 18 of the resistance 8 in this case is connected at an intermediate point on the inductance 6, that is to say, the resistance 8, instead of being connected in parallel with the capacitance 16 alone, is connected in parallel with the capacitance 16 and a portion of the inductance 6. This alteration is a further refinement the use of which is optional, and the function of which will be explained in connection with the graphs shown in Fig. 4 of the drawing.

In order to determine the character of the reaction of an amplifier embodying the foregoing coupling circuits I have found it convenient to use a method in which a simple sharply tuned circuit is used as a standard of comparison. For this purpose constant frequency energy is supplied from a source through a very loose coupling to such a sharply resonant circuit, and at any given fre-

quency the amount of detuning needed to reduce the voltage across the resonant circuit alone to half of its maximum value is obtained. The curve D in Fig. 4 is a curve plotting these values, that is to say, the number of M. M. F.'s detuning needed to reduce the voltage across the resonant circuit to half its value plotted as a function of wave length. Curve E is a curve arbitrarily obtained from curve D by making each ordinate half of the value that it has in curve D. The region between the curves D and E is a region in which the characteristic of a commercial broadcast receiving amplifier should lie if best results are to be obtained.

The region above curve D represents broader tuning, or increased damping, equivalent to the introduction of more resistance in the tuned circuit. The region below curve D represents sharper tuning, or decreased damping, or the introduction of negative resistance into the circuit. If the circuit has an ideally efficient coil it would, of course, be desirable to approximate curve D, rather than to come in the region below curve D. The present specification that the curve fall in the region below curve D is based upon the assumption that the coil is not ideal, nor even as good as may soon be approached as design and manufacture improves, and it is therefore preferred that the departure from curve D, if any, be in the direction of a more selective circuit, equivalent to the use of a more efficient coil, but within the limit specified to prevent instability.

Essentially, what is desired is that the reactionless stage should be equivalent in its effect on the resonant circuit to a small pure and constant capacitance. It should be a pure capacitance in order to avoid changes in the sharpness of tuning in the resonant circuit by the introduction of positive or negative resistance, except for the introduction of a slight negative resistance within the limit previously defined. This requirement is doubly important because the reaction affects not only the last tuned circuit, when a selector consisting of tuned circuits cascaded directly together is employed, but also the prior tuned circuits, because, for example, the coupling therebetween must be increased if resistance is introduced into one of the later circuits, and this broadens the tuning of all of the circuits. The capacitance must be constant so that the last circuit may be tuned together with the preceding tuned circuits. The capacitance must be small in order not to diminish the tuning range available with a given variable condenser.

To determine the effect of coupling the amplifier, including the reactionless or transition stages 2 and 10, upon the sharply tuned circuit, I proceed as follows:

The amplifier being investigated is connected to the said resonant circuit and, the

detuning needed to obtain half the maximum voltage is again ascertained. If the characteristic curve for the tuned circuit when working into the amplifier lies above the region between the curves D and E a receiver embodying the circuits would tune broadly, and interference would tend to increase. If the curve lies below the region defined between the curves D and E the receiver would tend to tune too sharply, and would be apt to be too critical in operation and to lead to distortion by selectively amplifying the carrier and side band frequencies within the modulation range, and in extreme cases to lead to oscillation.

Suppose now that the inductance 6 and resistance 8 have been substantially increased in magnitude and that their relative magnitudes have been adjusted for neutralization when no succeeding circuit is hung onto the output circuit of tube 2. As is explained in my Patent No. 1,620,661, previously mentioned, if a capacitance is hung onto the anode terminal of resistance 8 there is increased feed forward through the tube and consequently increased degeneration or damping. If a capacitance is hung at the other terminal of the resistance 8 there is increased feed back and consequent regeneration. An intermediate point may be selected for neutralization, but such neutralization is not accurate over the wave length band when the inductance 6 and resistance 8 have been greatly increased in impedance, and furthermore, the coupling to the succeeding tube 10 is inefficient because only a portion of the potential across the impedance of the output circuit of tube 2 is applied to the input circuit of tube 10.

I therefore prefer to couple the input circuit of tube 10 to the anode terminal of the resistance 8. This causes feed forward and damping in the input circuit of tube 2, and results in a reaction curve such as the dotted curve F in Fig. 4. This curve, it will be observed, lies above curves D and E, showing the broadness of the resonance curve of the tuned circuit, or the increased damping caused by the capacitive load on the anode terminal of resistance 8. Some capacitive shunting of the output circuit of tube 2 is inevitable, and for this reason I prefer as a next step to slightly decrease the magnitude of resistance 8 relative to the magnitude which it would have if properly increased (at some intermediate frequency) for neutralization of the feed back caused by inductance 6. A decrease in the magnitude of resistance 8 of about 300 ohms diminishes the feed forward through tube 2, and leads to a curve like the solid curve G in Fig. 4. This curve falls below the curves D and E at the low frequencies, and there shows feed back or regeneration, but this cannot be cured simply by again partially increasing resistance 8 for more degeneration, because curve G at the

high frequencies already lies above curves D and E, and therefore this region already has degeneration.

It is obvious from an inspection of both curve F and curve G that the real difficulty is that the slope of the reaction curve, when a constant capacitance is hung onto the output circuit of tube 2, differs from the slope of the desired reaction curve. By loading a variable capacitance onto the output circuit of tube 2 and making this capacitance increase at the low frequencies increased damping may there be obtained, as is desired, and by making this capacitance decrease at the high frequencies increased regeneration may there be obtained, as is also desired, in order to change the slope of curve G.

To this end the output circuit of tube 10 is made naturally resonant to a frequency lower than the working frequency range. This circuit is therefore capacitive for frequencies in the working frequency range, and has diminishing impedance with increasing frequency. This, in turn, causes diminishing gain in tube 10 with increasing frequency which, in turn, causes diminishing apparent input capacitance in tube 10 with increasing frequency. This variation is in the proper sense to correct the slope of curve G, and the range of variation may be controlled, but the nature or rate of variation throughout the range cannot be exactly controlled. As a result a reaction curve like the dotted curve A in Fig. 4 is obtained. It will be observed that the general or average slope of curve A is about what is desired, but that the curvature differs from the desired curvature, for the curve A shows a regenerative tendency in the middle of the frequency range.

By adding the condenser 16 in the manner shown in Fig. 1 or in Fig. 2 the curve B is obtained, and this, it will be observed, is a great improvement, for the curve is fairly regular throughout most of its range and is generally similar in configuration to the curves D and E, as well as lying therebetween. However, this curve has an undesirable irregularity near the shorter wave length end of the range, say at 250 meters, and it is with a view to obviate even this minor defect that the arrangement shown in Fig. 3 may be employed. The latter arrangement results in a curve like the curve C, which obviously fulfills all that is to be expected and desired. If the amplifier were coupled to a complete selector consisting of cascaded tuned circuits, instead of merely to a single tuned circuit, the nature of the curves would remain essentially similar, but the curves would be elevated to have higher ordinates, more detuning being needed because of the increased damping due to the coupled circuits. The percentage variation due to reaction would then be reduced, since the reac-

tion would not so greatly affect the coupled circuits of the selector. Accordingly, when the problem here presented is solved for a single tuned circuit it is solved for the worst case, and is therefore also solved for the case where the complete selector is employed. It also follows that such irregularities as may exist in the curves when the amplifier is connected to a single resonant circuit are very greatly smoothed out when the amplifier is connected to a complete selector. It may further be mentioned that curves A and B have been exaggerated in the drawing, even as applied to the reaction upon a single tuned circuit, in order to emphasize the faults to be illustrated.

The untuned output circuit comprising a small inductance in series with an inductance free resistance shunted by a small capacity, together with coupling means to a following tube, is especially valuable for creating in the input circuit of the preceding tube a relatively small and constant input capacity value, as well for eliminating reaction from the tube. By this is meant the elimination of any resistance component across the input of the tube, whether positive or negative. In other words, the use of such an output circuit in place of the ordinary transformer or resistance coupled output circuit gives to the tube an input characteristic which is essentially similar to that of a fixed loss free condenser. The magnitude of this equivalent condenser is small, being of the order of 20 micro micro farads with present day receiving tubes having a grid to plate capacitance of the order of three micro micro farads and an amplification constant of the order of 12. The capacitance value is about the same even when other tubes are used.

One important use for such an output circuit is in connection with an untuned amplifier for the amplification of a radio signal selected by a sharply tuned selector circuit comprising a cascade arrangement of loosely coupled resonant circuits. It is essential in such a system that the last tuned circuit be free to oscillate with its own natural damping characteristics in order that the desirable selectivity characteristics of the selector be retained. It is also desirable to have the amplifier input act as a fixed capacitance in order that the various tuned circuits in the selector may tune alike, for otherwise it would be necessary to make the last tuned circuit have a shaped condenser plate in order to make up for variations in the amplifier input capacity.

The application of the foregoing invention, in any of the forms shown in Figs. 1, 2, and 3, to such a complete receiver, is illustrated in Fig. 5, referring to which it will be observed that the receiver consists first of a selector, which may be of the type described in my copending application, Ser. No.

205,935, filed July 15, 1927, and which may optionally include the improvements set forth in my copending application Ser. No. 243,790, filed December 31, 1927, and a copending application of Lester L. Jones and Jacob Yolles, Ser. No. 408,160 filed October 29, 1929. The selector is followed by an amplifier of fixed circuit constants, such as that described in my Patent No. 1,675,287 issued June 12, 1928, and in my copending application Ser. No. 205,934, filed July 15, 1927, since issued as Patent No. 1,770,525, and which optionally may embody the improvements disclosed in my copending applications, Ser. No. 397,633, filed October 5, 1929, and Ser. No. 402,379 filed October 25, 1929. The selected and amplified energy is rectified in a suitable detector 30, and the resulting audio frequency energy may be further amplified, if desired, in an audio frequency amplifier 32, after which it may be translated in an appropriate translating device such as a loud speaker 34.

Considering the schematic wiring diagram more in detail, it will be observed that the last tuned circuit of the selector circuit 36 acts also as the input circuit for the first tube 2 of the amplifier. Between the first tube 2 and the second tube 10 of the amplifier a coupling arrangement may be used, such as those described in Figs. 1, 2, and 3 of the drawing, and which in this case is similar to the last of these. This coupling circuit comprises an output circuit including an inductive impedance 6, a condenser 16 in series therewith, and a neutralizing or feed forward resistance 8 arranged in parallel with the condenser 16 and a portion of the inductance 6, and a bifilar wound coupling transformer 20 the primary of which is connected across the output circuit. As is indicated on the wiring diagram, the bifilar wound transformer 20 preferably consists of separated halves or coils connected in series and wound in opposite directions, in order to reduce external magnetic coupling therewith, although other coils suitably shielded might be used. The inductance 6 similarly may consist of two separated portions wound in opposite directions.

Tube 10 has a large inductance output transformer serving to give tube 10 an input capacitance which rises with decreasing frequency which helps keep tube 2 reactionless, besides automatically tuning the input circuit of tube 10.

The complex output circuit described makes the tube 2 almost perfectly reactionless, and the input circuit thereof acts merely as a small loss free condenser of fixed capacitance connected across the last tuned circuit 36 of the selector.

Another important use to which my reactionless coupling circuit may be put is for an intermediate stage in an untuned amplifier. I refer especially to the cascaded un-

tuned amplifier of the automatically tuned type described in Patent No. 1,673,287, issued June 12, 1928, and further described in my copending application Ser. No. 205,934 filed July 15, 1927, since issued as Patent No. 5 1,770,525, and in a copending application of Lester L. Jones and Jacob Yolles, Ser. No. 403,161, filed Oct. 29, 1929. The design of this type of amplifier is relatively simple, starting back at the detector tube, for this 10 tube has at radio frequencies a relatively small and constant input capacitance and is free from reaction. The suitably large inductance in the output circuit of the last radio frequency stage therefore creates a rising 15 input capacitance with lower frequency characteristic in this stage, which is suitable for automatic tuning.

If a preceding radio frequency amplifier 20 stage is coupled directly thereto this stage is not suitable for automatic tuning over the same frequency range because its output circuit is held nearly resonant to the various frequencies in the lower frequency portion of 25 the range. However, with respect to frequencies in the higher frequency portion of the range its output circuit is resonant to a relatively lower frequency and therefore the input circuit of the preceding stage may be 30 automatically tuned to frequencies in the higher frequency portion of the range. In general, the full working frequency range 35 may be divided into as many portions as desired, and a similar number of stages provided each of which is automatically tuned to a different one of the frequency portions. However, it is desirable to design each stage 40 for as large a frequency range as it can efficiently automatically tune to, and to use only so many stages arranged directly in cascade as may prove necessary to cover the full 45 working frequency range, because the cascaded group consists, in effect, of only one accurately tuned stage and a remainder of less efficient stages. If greater gain and 50 more stages are desired in the amplifier it is therefore preferable to have these stages automatically tuned over the full working frequency range, rather than to divide the range into smaller portions, but it then is impossible to cascade the stages directly together because the necessary relation that the 55 successive coupling circuits have successively decreasing natural frequencies cannot then be fulfilled.

It therefore is desirable to introduce at this point a reaction free stage as an intermediate link circuit so as to permit the further efficient use of additional automatically 60 tuned stages in the multi-stage amplifier. The use of the reaction free coupling circuit herein disclosed gives to the tube preceding it a constant capacitance and reaction free 65 input characteristic similar to that found in the detector tube. The design of the first

few stages of the amplifier then becomes a mere duplication of those constituting the last stages, and efficient use of automatic tuning may again be had in the same amplifier system.

Such an amplifier arrangement is here illustrated in Fig. 6, merely by way of showing an additional use of my present reactionless coupling stage. The amplifier circuit itself is not claimed in this application, it being described more in detail and claimed in the copending application of Lester L. Jones and Jacob Yolles, Ser. No. 403,161, filed October 29, 1929, previously mentioned. Referring to Fig. 6, the antenna circuit 70 is coupled to a tunable selector 42, the last tuned stage 44 of which is coupled to a radio frequency amplifier 46. The amplifier 46 comprises a reactionless or link stage 48 followed by two automatically tuned amplifier stages 50 in turn followed by another reactionless or link stage 52 which separates the automatically tuned stages 50 from an additional pair of automatically tuned amplifier stages 54. The amplifier output is supplied 75 to a detector tube 56, the rectified output from which may, if desired, be further amplified in an audio frequency amplifier 58, the output of which is translated in any suitable translating device here exemplified by 80 a loud speaker 60.

It will be observed that the reactionless stages 48 and 52 have output circuits similar to those shown in Figs. 3 and 2 of the drawing, respectively, it not being necessary for 100 stage 52 to be as perfectly reactionless as stage 48, because stage 52 does not react upon a sharply tuned circuit, as does stage 48. It will be understood that the illustrated output circuits may, if desired, be replaced 105 by that shown in Fig. 1.

It is preferred to use automatic tuning in groups of two tubes, as shown, but the groups may range from one to three tubes, as described previously.

It will be noted that there is a free grid inductance 62 in series with the grid of the reactionless stage 52, and a free grid inductance 64 in series with a control electrode of the detector tube stage 56. This free grid inductance is so dimensioned that it tends to series resonate with the input capacitance of the tube at a frequency higher than the highest frequency of the working frequency range. It therefore compensates for a tendency of the amplification to fall off at the higher frequencies due to the higher frequencies being shunted by the tube input 110 capacitance.

Returning again to the coupling circuit, as a sample of the quantitative values which may be employed, and referring to the coupling arrangement shown in Fig. 2, and assuming that standard tubes having the following characteristics:—grid to plate ca- 115

5 capacitance equals 3 M. M. F., amplification factor equals 13, tube conductance equals 1300 micromhos, are used, the resistance 8 may have a resistance of say 2800 ohms, the 10 capacitance 16 a value of say 18 M. M. F.'s, the inductance 6 may be wound of say two 15 85 turn halves in series, having 240 microh. total inductance, accompanied by an inherent resistance of only about 100 ohms, while the 20 transformer 20 may consist of two 200 turn halves in series in both its primary and secondary, and have a total inductance of 1100 microh. These constants are suitable for a 25 range of 500 to 1500 kilocycles, or say 200 to 600 meters.

15 Referring to the modification shown in Fig. 3, and assuming a standard tube is used as before, having a grid to plate capacitance of say 3 M. M. F.'s an amplification 20 constant of say 13, and a tube conductance of say 1300 micromhos, the resistance 8 may have a value of say 2800 ohms, the condenser 16 a value of say 18 M. M. F.'s, the portion of the inductance 6 connected in 25 shunt with the resistance 8 may have a value of say 39 microh., the remainder of the inductance 6 connected in series with the resistance 8 may have a value of say 244 microh., while the mutual inductance between the portions of the inductance 6 may 30 have a value of say 27 microh., the inherent resistance in inductance 6 being only about 100 ohms, the transformer 20 meanwhile having an inductance of 1240 microh.

35 The stage including the following tube, or tube 10, if arranged as an additional transition stage for perfecting the reactionlessness of tube 2, should have an output inductance 11 which may consist of about 600 turns random 40 wound and having an inductance of about 4.5 millihenries, assuming the tube 10 to be a standard tube of characteristics similar to those already mentioned in the case of tube 2.

It should be understood that while I prefer 45 a reactionless link consisting of two transition stages, so that the second may correct for residual reaction through the first, the present invention, in so far as it relates to the beneficial effect obtained by the provision of a 50 capacitance in parallel with the feed forward resistance, is applicable to a single reactionless stage. For example, if the link stage worked into a system of very low capacitance, say a few M. M. F., the reaction characteristic 55 would have approximately the correct slope even without the use of a second transition stage, but would nevertheless have the undesirable regenerative reaction in the middle of the working frequency range which is eliminated by the use of the parallel connected 60 capacitance. It also is of utility in an arrangement such as is shown in Fig. 6, in which the tube following the reactionless stage only 65 partially helps to load the output circuit thereof with a desired corrective capacitance,

inasmuch as this tube also acts as the first tube of a pair of automatically tuned stages, and therefore cannot have in its output circuit a sufficiently large inductance to act to the optimum as a second transition stage.

70 The circuit arrangement of my invention, the manner of applying it, and its advantages, will for the most part be apparent from the foregoing description thereof. It will also be understood that, relative to my invention as set forth in my copending application, Ser. No. 205,934 already referred to, since issued as Patent No. 1,770,525, the present improvements may be considered in two aspects, one of which consists in the 75 changes made to the output circuit of the first tube, that is to say, to the shunt circuit connected in parallel with the coupling circuit, and the other of which consists in the successful introduction of transformer coupling in this type of circuit and in appropriate changes in the accompanying circuits, the transformer circuit leading to advantages 80 previously pointed out.

85 It will be apparent that while I have shown and described my invention in the preferred forms, many changes and modifications may be made in the structures disclosed without departing from the spirit of the invention, 90 defined in the following claims.

95 I claim:

100 1. An amplifier stage comprising an electron emission tube and associated input and output circuits, means in said output circuit to make the reaction through the tube regenerative throughout the working frequency range, means to neutralize the regeneration in order to prevent reaction upon the input circuit, and transformer means connected in parallel with said output circuit for coupling the output circuit of the tube to a succeeding 105 circuit, said transformer means having a low resistance relative to that of the output circuit.

110 2. An amplifier stage comprising an electron emission tube, an inductive impedance in the output circuit of said tube, a resistance in series with said inductance, a capacitance arranged in shunt with said resistance, and additional means for coupling the output circuit of the tube to a succeeding circuit.

115 3. An amplifier stage comprising an electron emission tube, an inductive impedance in the output circuit of said tube, a resistance in series with said inductance, a capacitance arranged in shunt with all of said resistance and a portion of said inductance, and additional means for coupling the output circuit of the tube to a succeeding circuit.

120 4. A reactionless amplifier stage comprising an electron emission tube, an inductive impedance in the output circuit of said tube in order to make its reaction regenerative over the working frequency range, a resistance in series with said inductance for 125

causing a feed forward reaction opposed to the regenerative feed-back reaction, a capacitance arranged in shunt with said resistance, and additional means for coupling the output circuit of the tube to a succeeding circuit.

5. A reactionless amplifier comprising a first transition stage having an output circuit arranged to make the stage nearly reactionless, a second transition stage having an output circuit arranged to cause the input circuit thereof to have a variation in apparent input capacitance with frequency designed to correct the residual reaction in the first transition stage, and a bifilar or equivalent closely coupled transformer for coupling the first and second stages in order to transfer the input capacitance of the second stage to the output circuit of the first stage.

6. A reactionless amplifier comprising a first electron emission tube, an inductive impedance in the output of said tube, a resistance in series with said inductance, a capacitance arranged in shunt with said resistance, a second electron emission tube, an output circuit therefor arranged to give the input circuit thereof a decreasing apparent capacitance with increasing frequency, and additional means for coupling the output circuit of the first tube to the input circuit of the second tube.

7. A radio receiving circuit comprising a selector having variable circuit constants, a vacuum tube amplifier having fixed circuit constants, and means coupling said amplifier to said selector comprising means to make the reaction of the first amplifier tube regenerative throughout the working frequency range, means to neutralize the consequent regeneration in order to prevent reaction by the amplifier upon the selector, and bifilar transformer means for coupling the output circuit of the first amplifier tube to the input circuit of the second amplifier tube.

8. A radio receiving circuit comprising a selector, a cascade vacuum tube amplifier, and means coupling said amplifier to said selector comprising the first tube of said amplifier, an inductive impedance in the output circuit of said first tube, a resistance in series with said inductance, a capacitance arranged in shunt with said resistance, and means coupling the output circuit of the first tube to the input circuit of the next tube of the amplifier.

9. A radio receiving circuit comprising a selector, a cascade vacuum tube amplifier, and means coupling said amplifier to said selector comprising the first tube of said amplifier, an inductive impedance in the output circuit of said first tube, a resistance in series with said inductance, a capacitance arranged in shunt with all of said resistance and a

portion of said inductance, and additional means for coupling the output circuit of the first tube to the input circuit of the next tube of the amplifier.

10. A radio receiving circuit comprising a selector having variable circuit constants, a cascade vacuum tube amplifier having fixed circuit constants, and means coupling said amplifier to said selector comprising the first tube of said amplifier, an inductive impedance in the output circuit of said first tube in order to make its reaction regenerative over the working frequency range, a resistance in series with said inductance for causing a feed forward reaction opposed to the regenerative feed back reaction, a capacitance arranged in shunt with said resistance, and means coupling the output circuit of the first tube to the input circuit of the next tube of the amplifier.

11. A radio receiving circuit comprising a selector having variable circuit constants, a cascade vacuum tube amplifier having fixed circuit constants, and means coupling said amplifier to said selector comprising the first tube of said amplifier, an inductive impedance in the output circuit of said first tube in order to make its reaction regenerative over the working frequency range, a resistance in series with said inductance and a capacitance arranged in shunt with said resistance for causing a feed forward reaction opposed to the regenerative feed back reaction in order to prevent reaction by said amplifier upon said selector, and additional transformer means for coupling the output circuit of the first tube to the input circuit of the next tube of the amplifier.

12. A radio receiving system comprising first and second vacuum tubes and coupling means therefor comprising a transformer and a shunt circuit arranged in parallel with the primary of said transformer, said shunt circuit consisting of a series combination of a capacitance and an inductance, and a resistance connected in parallel with said capacitance.

13. A radio receiving system comprising first and second vacuum tubes and coupling means therefor comprising a very closely coupled transformer and a shunt circuit arranged in parallel with the primary of said transformer, said shunt circuit consisting of a series combination of a capacitance and an inductance, and a resistance connected in parallel with said capacitance and a portion of said inductance.

14. A radio receiving system comprising a selector, a cascade vacuum tube amplifier, means coupling the first and second vacuum tubes of the amplifier comprising a bifilar wound transformer and a shunt circuit arranged in parallel with the primary of said transformer, said shunt circuit including a series combination of a capacitance and an

inductance, and a resistance connected in parallel with said capacitance, and means coupling the second and third vacuum tubes of the amplifier arranged to prevent residual reaction through the first tube by the amplifier on the selector.

15. A radio receiving system comprising a selector having variable circuit constants in order to permit tuning thereof, a cascade vacuum tube amplifier having fixed circuit constants, and means coupling the first and second vacuum tubes of the amplifier comprising a transformer and a shunt circuit arranged in parallel with the primary of said transformer, said shunt circuit including a series combination of a capacitance and an inductance, and a resistance connected in parallel with said capacitance.

16. A radio receiving system comprising a selector having variable circuit constants in order to permit tuning thereof, a cascade vacuum tube amplifier having fixed circuit constants, and means coupling the first and second vacuum tubes of the amplifier comprising a transformer and a shunt circuit arranged in parallel with the primary of said transformer, said shunt circuit including a series combination of a capacitance and an inductance, and a capacitance and inductance free resistance connected in parallel with said capacitance and a portion of said inductance.

17. A radio receiving system comprising a selector having variable circuit constants in order to permit tuning thereof, a cascade vacuum tube amplifier having fixed circuit constants, means including a tuned circuit for coupling the selector to the first tube of the amplifier, and means coupling the first and second tubes of the amplifier comprising a bifilar transformer and a shunt circuit arranged in parallel with the primary of said transformer, said shunt circuit including a series combination of a capacitance and an inductance, and a capacitance and inductance free resistance connected in parallel with said capacitance and a portion of said inductance.

18. A reactionless amplifier comprising a first electron emission tube, an inductive impedance in the output of said tube, a resistance in series with said inductance, a capacitance arranged in shunt with said resistance, a second electron emission tube, an output circuit therefor arranged to give the input circuit thereof a decreasing apparent capacitance with increasing frequency, and a bifilar transformer or equivalent closely coupled transformer means for coupling the output circuit of the first tube to the input circuit of the second tube.

19. A radio receiving circuit comprising a selector, a cascade vacuum tube amplifier, and means coupling said amplifier to said selector comprising the first two stages of said amplifier, the first stage having an output circuit including an inductive impedance, a resist-

ance in series with said inductance, and a capacitance arranged in shunt with said resistance, the second stage having an output circuit arranged to give the input circuit thereof a decreasing capacitance characteristic with increasing frequency, and means coupling the output circuit of the first tube stage to the input circuit of the next stage of the amplifier.

20. A radio receiving circuit comprising a selector, a cascade vacuum tube amplifier, and means coupling said amplifier to said selector comprising the first two stages of said amplifier, the first stage having an output circuit including an inductive impedance, a resistance in series with said inductance, and a capacitance arranged in shunt with said resistance, the second stage having an output circuit arranged to give the input circuit thereof a decreasing capacitance characteristic with increasing frequency, and a bifilar transformer or equivalent closely coupled transformer means coupling the output circuit of the first tube stage to the input circuit of the next stage of the amplifier.

21. A reactionless amplifier comprising a vacuum tube, an inductance in the output circuit thereof arranged to make the reaction of the tube regenerative, a resistance in series with said inductance for opposing the regenerative reaction of the tube, said inductance and resistance being greatly increased in magnitude over the correct value for making the tube reactionless in order to increase the gain therein, and means arranged to prevent residual reactions through the tube caused by the said increase in the output impedance thereof.

22. A reactionless amplifier comprising a vacuum tube, an inductance in the output circuit thereof arranged to make the reaction of the tube regenerative, a resistance in series with said inductance for opposing the regenerative reaction of the tube, said inductance and resistance being greatly increased in magnitude over the correct value for making the tube reactionless in order to increase the gain therein, and a capacitance arranged in parallel with the said resistance in order to prevent a residual reaction through the tube caused by the said increase in the output impedance thereof.

23. A reactionless amplifier comprising a first vacuum tube, an inductance in the output circuit thereof arranged to make the reaction of the tube regenerative, a resistance in series with said inductance for opposing the regenerative reaction of the tube, said inductance and resistance being increased in magnitude to about twice the correct value for making the tube reactionless in order to increase the gain therein, and a second vacuum tube coupled to the output circuit of the first and arranged to prevent a residual reaction through the first tube caused by the said doubling of the output impedance thereof.

24. A reactionless amplifier comprising a first vacuum tube, an inductance in the output circuit thereof arranged to make the reaction of the tube regenerative, a resistance in series with said inductance for opposing the regenerative reaction of the tube, said inductance and resistance being greatly increased in magnitude over the correct value for making the tube reactionless in order to increase the gain therein, a second vacuum tube coupled to the output circuit of the first and arranged to prevent a residual reaction through the first tube, and a capacitance arranged in parallel with the aforesaid resistance in order to prevent an additional residual reaction through the first tube, said residual reactions being caused by the said doubling of the output impedance of the first tube.
25. A reactionless amplifier comprising a first vacuum tube, an inductance in the output circuit thereof arranged to make the reaction of the tube regenerative, a resistance in series with said inductance for opposing the regenerative reaction of the tube, said inductance and resistance being increased in magnitude to about twice the correct value for making the tube reactionless in order to increase the gain therein, a second vacuum tube coupled to the output circuit of the first and arranged to prevent a residual reaction through the first tube, and a capacitance arranged in parallel with the aforesaid resistance in order to prevent an additional residual reaction through the first tube, said residual reactions being caused by the said doubling of the output impedance of the first tube.
26. A radio receiving circuit comprising a selector tunable over a given frequency range, a reactionless amplifier comprising a first vacuum tube, an inductance in the output circuit thereof arranged to make the reaction of the tube regenerative, a resistance in series with said inductance for opposing the regenerative reaction of the tube, said inductance and resistance being increased in magnitude to about twice the correct value for making the tube reactionless over the whole frequency range in order to increase the gain in the tube, a second vacuum tube coupled to the output circuit of the first and arranged to prevent a residual reaction through the first tube, and a capacitance arranged in parallel with the aforesaid resistance in order to prevent an additional residual reaction through the first tube over a portion of the frequency range, said residual reactions being caused by the said doubling of the output impedance of the first tube.
